UNITED STATES PATENT OFFICE.

HERMAN J. SCHARNAGEL, OF TOMPKINSVILLE, NEW YORK, ASSIGNOR TO THE SPERRY GYROSCOPE COMPANY, OF BROOKLYN, NEW YORK, A CORPORATION OF NEW YORK.

FLUID-CURRENT MOTOR.

1,401,651.

Specification of Letters Patent. Patented Dec. 27, 1921.

Application filed June 26, 1918. Serial No. 242,087.

To all whom it may concern:

Be it known that I, HERMAN J. SCHARNAGEL, a citizen of the United States, residing at 85 Hannah street, Tompkinsville, Staten Island, in the county of Richmond and State of New York, have invented certain new and useful Improvements in Fluid-Current Motors, of which the following is a specification.

10 This invention relates to fluid current motors. More specifically it relates to mechanism for maintaining the speed of such a motor substantially constant.

While my invention is capable of use either as a propeller or as a windwheel, both of which are included under the generic expression fluid current motor, I have selected for the present specific embodiment a windwheel designed for use on an aeroplane to

20 drive a generator or other device.

A windwheel for such use should possess the following characteristics among others. It should be of simple design, of small weight and should occupy a minimum space for 25 obvious reasons. It should also develop the required power without presenting undue head resistance; which would retard the forward travel of the aeroplane; so that high angular velocity is necessary. As centrifugal 30 force varies as the square of the angular velocity, it is obvious that the device must withstand severe stresses. It should also hold a substantially constant speed in spite of the fact that the relative velocity of the 35 wind and the load carried by the windwheel may vary over comparatively wide limits.

The principal object of the present invention is to provide a motor which possesses the above mentioned characteristics and 40 meets the above mentioned conditions. Further objects and advantages will appear as the invention is hereinafter developed.

45 Referring to the drawings which illustrate what I now consider the preferred forms of my invention:

Figure 1 is a rear elevation of one form of my invention.

Fig. 2 is a central horizontal section of the form illustrated in Fig. 1 showing the 50 device mounted on a generator shaft.

Fig. 3 is a view similar to Fig. 2 but taken substantially on an axial plane at right angles to the plane on which Fig. 2 is taken.

Fig. 4 is a sectional fragmentary detail view illustrating a modification.

Fig. 5 is a section taken on the line 5—5 of Fig. 4.

Fig. 6 is a fragmentary front elevation of a further modification.

Fig. 7 is a view similar to Fig. 1 but illustrating further modifications.

Fig. 8 is a central horizontal section of the form illustrated in Fig. 7.

Fig. 9 is a view similar to Fig. 8 but taken substantially on an axial plane at right angles to the plane on which Fig. 8 is taken.

Fig. 10 is a section on the line 10—10 of Fig. 7.

Fig. 11 is a section on the line 11—11 of Fig. 9.

Fig. 12 is a section on the line 12—12 of Fig. 8.

Referring to Figs. 1 to 3 it will be seen that I have shown a hub 1 provided with a central tapering opening 2 adapted to seat 75 on the tapering end portion 3 of a shaft 5. The latter may be the shaft of a generator or other device of which the casing is designated 4. A nut 6 may be provided on the end of shaft 5 for holding the hub firmly 80 and non-rotatably on its seat.

A plurality of blades 7, 8 are connected to the hub 1 in such a manner as to cause the latter to rotate on its axis when said blades revolve. The blades 7, 8 are also so mounted 85 on hub 1 as to be capable of rotation about their own axes. Thus I have shown the web 9 of said hub provided with enlarged portions 10 in which the spindles 11 and 12 are

slidably and rotatably mounted. For a reason which will hereinafter appear I prefer to make these spindles in the form of tubes as shown. The blades 7, 8 are shown secured to spindles 11, 12 by means of rivets, the spindles 11, 12 having cut away portions 95 as illustrated to permit the riveting to be accomplished and to reduce the weight. In order to prevent the blades from moving outwardly due to centrifugal force I connect each of the blades to the hub 1 by means 100 of a wire or rod 14. Each of the rods 14 extends through a corresponding one of spindles 11, 12 and is provided with an enlarged portion 15 at its outer end which may be secured to the outer end of the blade and 105 spindles by means of through-pins 16. The

latter are shown as upset at opposite ends to hold them in place. The other end of each of said rods 14 may be threaded to receive a nut 17 adapted to seat against a shoulder 18 provided on enlarged portions 10. The rods 14 besides performing the above mentioned function also constitute a part of the speed governing mechanism of which the remainder may be constructed substantially as follows.

A weighted arm is secured to each of spindles 11 and 12. Each of said arms is bifurcated at its inner end to clear the enlarged portion 19 which receives the shaft 5. The arm 20 for spindle 11 is shown provided with a single weight 21 while the arm 22 for the spindle 12 is provided with two weights 23 connected by a bridging piece 24. Normally, *i. e.* when the device is not in operation, the weight 21 lies between weights 23 in engagement with the member 24. It will also be noted, on inspection of Fig. 3, that the last mentioned member and the weight 21 are cut away to clear the nut 6 and end of shaft 5. To secure each of the arms 20, 22, fixedly but adjustably to its corresponding spindle 11 or 12, I provide the inner ends of each of the leg portions of said arms with a radial slit 25 and a screw 26 for drawing the parts 27, 28 together.

When the device rotates the weighted arms move away from each other due to centrifugal force thus rotating the blades 35 about their own axes but in opposite directions. In order to increase the reliability of operation, I provide means for causing the blades to rotate equal amounts. This means may assume the form of gear teeth 40 29 provided on the inner ends of arm 20 and adapted to mesh with corresponding teeth provided on the inner ends of arm 22.

The rods or wires 14 may be employed to oppose rotation of spindles 11 and 12 and 45 blades 7 and 8, by the weighted arms 20, 22, by fixedly securing the inner ends of rods 14 to the members 10. I prefer to make the last mentioned connection adjustable as shown clearly in Fig. 2. Each of said rods is provided with an enlarged portion 31 adapted to be gripped between oppositely located set screws 32 screwed into the corresponding one of members 10. By slackening off on set screws 32 and turning the rods 14 at the 50 squared end portions 33 the initial torsion placed on said rods may be regulated and held in regulated condition by again tightening said screws. My motor is designed to operate substantially as follows.

Assuming that the rods are placed in torsion and tending to hold the weighted arms 20, 22 in the position shown in Fig. 3, it will be obvious that as the fan speeds up the arms 20, 22 will move away from each other until such a speed is reached that the

centrifugal force on said arms is balanced by the torsional forces exerted by rods 14. This speed will then be maintained substantially constant for if the speed should pick up above this amount the weighted arms 20, 22 would spread farther apart, due to the increase in centrifugal force, and increase the pitch of the blades so that the torque impressed by the wind would decrease until the predetermined constant speed was again reached. If the speed should drop below the predetermined constant amount the centrifugal force on the weighted arms would decrease and the torsional force of rods 14 would turn the blades to decrease the pitch of the latter to cause the device to speed up. By regulating the torsion on rods 14, as previously described any value of constant speed at which the motor will be held may be selected.

A substantially hemispherical or dome-shaped cover or hood 34 may be secured to the hub 1 at the front thereof by means of screws 35. It will be noted that the external diameters of the hub 1 and casing 4 are the same and equal to the largest external diameter of the hood 34 so that the head resistance is reduced to a minimum.

My invention may be modified in various ways. Thus instead of adjustably securing the inner ends of rods 14 as shown in Figs. 1 and 2, the structure illustrated in Figs. 4 and 5 may be adopted. In the latter views parts corresponding to those in Figs. 1 and 2 have been designated by the same reference numerals with a prime added. In this form the set screws 32' do not directly engage the enlarged portion 31' of the rod but engage instead the reduced shank portion 37 of nut 17'. The latter which is of considerable length is internally threaded to receive screw threads provided on the portion 31' thus providing a large bearing surface against tension on the rod 14'. The rod 31' may be secured against turning with respect to nut 17' by means of a pin 35' passing through both of said members and the nut 17' may be rotated to adjust the torsion on the rod 14' by means of a suitable tool inserted into holes 36 in said nut. The screws 32', employed to hold the parts in adjusted position, are shown at right angles to each other instead of being diametrically opposed.

Attention is called to the fact that in Figs. 1 and 2, the outer ends of the blades 7 and 8 are shown as straight and the inner ends curved to conform to the shape of the hood 34. This arrangement, although desirable in some respects, is by no means indispensable as the blades may be curved at both ends in the manner illustrated in Fig. 6. Furthermore, instead of placing the spindles 11, 12 behind the blades as indicated in Figs. 1 and 2, they may be con-

nected to the blades at the front thereof as indicated in Fig. 6.

The form of invention illustrated in Figs. 7 to 9 possesses many features in common with the form illustrated in Figs. 1 to 3, similar parts being designated by the same reference numerals. The former will be found to differ from the latter in the form of blades employed, the means for securing the torsion wires 14 to the blades and hub and in the arrangement of the governor weights.

Referring to Figs. 7, 8 and 10 it will be seen that each blade comprises a plurality of plates 57, 57'. The plate 57 is shown secured to spindle 11 by means of rivets 13 and the plate 57' is secured at its edges to the edges of plate 57 so as to lie on the side of the spindle opposite the last mentioned plates. The junction of plates 57, 57' may be effected by riveting at 58. One of the important advantages of this type of blade is that a smooth surface is presented to the wind thus preventing the formation of eddies, thereby enhancing both the reliability and efficiency of the motor.

The rods 14, instead of being connected to the hub 1 in the manner shown in Figs. 1 and 2, are shown connected to said hub by means of structure practically identical to that shown in Figs. 4 and 5 except that the nut 17' is provided with a knurled head instead of openings 36. Furthermore the rods 14 are shown connected to the blades, or blade spindles, by means of the following structure.

Each of the rods is threaded at its outer end to enter a nut 60 provided with a reduced shank portion 61 adapted to enter the outer end of a corresponding one of spindles 11, 12. Each nut 60 and end of rod 14 are provided with openings to receive a through pin 62. In order to lock the ends of said rods 14 against rotation, with respect to the spindles 11, 12, lugs 63 may be provided on said spindles as shown in Figs. 8 and 12, said lugs being adapted to enter notches 64 provided in each nut 60. By virtue of the last described structure the outer ends of rods 14 will not only be locked against rotation with respect to spindles 11, 12, but large bearing surfaces are provided to resist the tension due to centrifugal force.

In order to reduce the magnitude of the centrifugal force acting on the blades, I prefer so to design the governor weights that the centrifugal force acting on the latter, in the direction along spindles 11 and 12 will oppose that acting on said blades. Thus, referring to Figs. 8, 9 and 11, it will be seen that the center of gravity of each of weights 21', 23' lies, on the side of shaft 5, opposite the blade to which the particular weight is attached.

The operation of the form of invention

illustrated in Figs. 7 to 12 is substantially the same as that of the form shown in Figs. 1 to 3 and needs no further description. It should be noted that in both forms (see Figs. 3 and 9) the centers of gravity of the weights lie, normally, close to the plane including the axis of shaft 5 and parallel to spindles 11, 12. An important advantage flows from this arrangement, for when the speed of the motor changes, the distance between the centers of gravity and plane above mentioned changes rapidly. The governor is accordingly quickly responsive so that a practically uniform speed will be maintained at the predetermined value.

In accordance with the provisions of the patent statutes, I have herein described the principle of operation of my invention, together with the apparatus, which I now consider to represent the best embodiment thereof, but I desire to have it understood that the apparatus shown is only illustrative and that the invention can be carried out by other means. Also, while it is designed to use the various features and elements in the combination and relations described, some of these may be altered and others omitted, and some of the features of each modification may be embodied in the others, without interfering with the more general results outlined, and the invention extends to such use.

Having described my invention, what I claim and desire to secure by Letters Patent is:—

1. A fluid current motor comprising a hub, a plurality of blades mounted thereon for revolution about the axis of said hub and for rotation about their own axes, a plurality of weighted arms each fixedly connected to a corresponding blade for rotating said blade in response to centrifugal force, and a plurality of resilient members one for each of said blades and each anchored at its inner end to said hub for opposing the action of centrifugal force on said arm.

2. A fluid current motor comprising a hub, a plurality of blades rotatably mounted thereon and a plurality of torsionally resilient rods or wires, each of said rods being connected at one end to a point on one of said blades near the outer end thereof and connected at the other end to said hub.

3. A fluid current motor comprising a hub, a plurality of blades rotatably mounted thereon and means for preventing outward radial movement of said blades comprising a plurality of tension rods or wires each fixedly connected at one end to a corresponding one of said blades and fixedly connected at the opposite end to said hub.

4. A fluid current motor comprising a hub member, a blade rotatably secured to one side of the hub, and a combined torsion and tension wire secured at one point to a

- point on the blade adjacent the tip thereof and at another point to said member. 65
5. A fluid current motor comprising a hub, a plurality of blades rotatably mounted 5 thereon and connected for equal and opposite rotation, speed responsive means connected to at least one of said blades and a torsion rod or wire connected to one of said blades and to said hub. 70
10. 6. A fluid current motor comprising a hub, a blade rotatably mounted on said hub, a weighted arm for rotating said blade in response to centrifugal force and a torsion rod secured at one end to said blade and at the 15 other end to said hub. 75
15. 7. A fluid current motor comprising a hub, a blade rotatably mounted on said hub and a rod connecting said blade and hub for preventing outward radial movement of said 20 blade, said rod being non-rotatably secured to said blade and hub. 80
25. 8. A fluid current motor comprising a hub, a plurality of blades rotatably mounted on said hub about axes at an angle to the axis 25 of rotation of said hub, a plurality of weighted arms secured one to each blade and means normally but yieldingly holding said arms in a position in which the distance between the centers of gravity of said arms is less 30 than the distance between the pivotal points of said arms. 85
35. 9. A fluid current motor comprising a hub, a plurality of blades rotatably supported on said hub and extending in opposite directions at an angle to the axis of said hub, a plurality of arms one secured to each blade and extending at an angle to the axis of rotation of the latter, a plurality of weights secured one to each arm and means causing 40 said weights normally to engage. 90
45. 10. A fluid current motor comprising a hub, a hollow spindle rotatably carried by said hub, a blade secured to said spindle and a torsion wire in said spindle and secured at one end to the latter and at the other end to said hub. 95
50. 11. A fluid current motor comprising a hub, a plurality of blades rotatably mounted on said hub, a plurality of weighted arms each connected to a corresponding one of said blades at an angle to the axis of rotation of the latter and means normally causing said arms to assume a position in which they approach each other at their free ends. 105
55. 12. A fluid current motor comprising a hub, a blade mounted on said hub for rotation with respect thereto, speed responsive means for causing rotation of said blade, and means comprising a torsion wire connected to said blade and hub for opposing such rotation. 110
60. 13. A fluid current motor comprising a hub, a blade mounted on said hub for rotation with respect thereto, speed responsive 115
- means for causing rotation of said blade, and means comprising a torsion rod connected to said blade and hub for opposing such rotation, one of the connections of said rod being adjustable. 120
14. A fluid current motor comprising a hub member, a blade means for mounting said blade on said hub for rotation with respect thereto, and a tension wire extending between and secured to the hub and a point adjacent the tip of said blade. 125
15. A fluid current motor comprising a hub member, a hollow rib projecting therefrom, a blade secured to said rib, and a tension wire anchored to said hub and to the outer extremity of said rib adjacent its two ends. 130
16. A fluid current motor comprising a hub member, a blade secured to one side of the hub, and a tension wire secured adjacent one end to a point on the blade and near its other end on said member on the side opposite said blade. 135
17. A fluid current motor comprising a hub member, a blade rotatably secured to one side of the hub, and a combined torsion and tension wire secured adjacent one end to a point on the blade and near its other end on said member to the side opposite said blade. 140
18. A fluid current motor comprising a hub, a blade rotatably mounted thereon, means connected to said blade and responsive to centrifugal force for rotating said blade, and means connected to said blade for both opposing such rotation and supporting the blade against centrifugal forces on the same. 145
19. A fluid current motor or propeller comprising a hub portion mounted for rotation about an axis, a plurality of blades journaled in said hub for revolution therewith and rotation about their axes within the hub and a wire or rod extending along the back of said blade, and anchored at one end to the hub and at the other end to the blade. 150
20. A fluid current motor comprising a hub member, a blade rotatably secured to one side of the hub, and a combined torsion and tension wire secured adjacent one end to a point on the blade and near its other end to said member. 155
21. A fluid current motor comprising a hub member, a pair of blades rotatably secured to said hub, a centrifugally operated arm secured to each blade for turning the same oppositely, gearing connecting said blades for equal and opposite turning, and a combined torsion and tension wire secured near one end to a point on the blade and near its other end to said hub member. 160
- In testimony whereof I have affixed my signature. 165

HERMAN J. SCHARNAGEL.
